Attorneys

UNITED STATES PATENT OFFICE.

WILLIAM N. KIDDER, OF AUBURN, RHODE ISLAND.

DENTAL TRAY.

Application filed July 13, 1923. Serial No. 651,226.

- This invention relates to improvements in the construction of dental impression trays, and has for its object to provide a tray of this character having its body shaped to take a full-jaw impression and also having the front portion of the body removable, whereby the tray may be readily removed from the jaw after having taken an impression thereof.
- 10 A further object of this invention is the provision of an inturned cleavage ridge on the line of separation between the front section and the body portion.
- The invention further consists in the provision of a separate, separable, cooperating impression unit or cup adapted to be first applied to take the impression of a selected tooth or group of teeth which may be malformed or mal-posed and, after the impression material therein has hardened the main tray carrying its impression material is inserted into the mouth and the unit with the rest of the jaw is impressed therewith.
- 15 With these and other objects in view, the invention consists of certain novel features of construction, as will be more fully described, and particularly pointed out in the appended claims.
- 20 In the accompanying drawings:
- Figure 1 is a plan view showing my improved tray with the removable front section connected thereto.
- Figure 2 is the same as Figure 1, but showing a pair of individual impression units as being inserted into opposite sides of the tray for the purpose of taking a separate impression of a selected tooth or group of malformed or mal-posed teeth simultaneously with the taking of an impression of the rest 25 of the jaw.
- Figure 3 is a perspective view showing the body portion of my improved dental impression tray with the front section removed.
- Figure 4 is a perspective view of the front section removed from the body portion of the tray.
- Figure 5 is a sectional elevation on line 5—5 of Figure 4, of the front removable section.
- 30 Figure 6 is a section on line 6—6 of Figure
- ure 3, through the body portion of the tray.
- Figure 7 is a perspective view showing one half of one of the separate impression units.
- Figure 8 is a central section through the dental impression unit, taken on line 8—8 of Figure 2.
- Figure 9 is a sectional elevation showing the individual impression unit in the impression material in the main portion of the tray; also showing this unit as being itself filled with impression material.
- It is found in the practical construction of dental impression trays which are employed for taking full-jaw impressions, of advantage to form the tray with rearwardly-extending trough or channeled-shaped portions adapted to take impressions of the posterior teeth and the interdentulous spaces, and to form the front section removable and to provide this section with a fracture rib or ridge along its line of separation to facilitate the fracturing of the impression material to permit removal of the body of the tray from the jaw after having taken an impression of the mouth.
- It is also found of advantage to so shape the tray that it is adapted to receive independent impression units which are employed for taking a separate impression of the posterior teeth independently of the taking of an impression of the rest of the jaw, in the main portion of the tray whereby an accurate impression of mal-posed or malformed teeth, is obtained, and after the impression material therein has hardened the main tray carrying its impression material is inserted into the mouth and the unit with the rest of the jaw is impressed therewith. The tray body is then removed and subsequently the unit is split and removed from the tooth and replaced in its molded socket in the tray to complete the full impression in the tray.
- The following is a detailed description of such a dental impression tray by which these advantageous results may be accomplished:
- With reference to the drawings, 10 designates the body portion of my improved sectional dental impression tray, which is formed in channel or trough shape having outer edge walls 11 and inner edge walls 12,

the channel being preferably open as at 13 on its inner ends forming channel-shaped extensions adapted to take an impression of the posterior portion of the mouth including the posterior teeth and interdentalous spaces in the jaw.

As illustrated in Figure 3, a handle member 14 is provided with an upturned portion 15 where it is connected to the bottom of the body of the tray forming a substantially right-angled shoulder through which an opening 16 is formed for the reception of a guide tongue 17 of the removable section 18. This section is provided with an outer wall portion 19 which when in position serves to make a continuous outer wall about the body portion. This removable section is also provided with a bottom plate 20 which is a continuation of the bottom plate 21 of the main body portion, and the meeting edge of this removable section is turned upwardly as at 22 forming a sharp fracture ridge in this section, which is adapted to cause the plaster of this mold to crack along the line of this fracture ridge so that when it is desired to remove this section, this portion of the plaster will be removed therewith, thereby removing the front portion of the mold from the teeth permitting the main body portion of the tray to be much more readily removed from the rear or posterior portion of the mouth.

This removable section is also provided with an operating handle 23 which is adapted when in position, to lie in alignment with the handle 14 of the main tray and rest thereupon for the purpose of supporting this removable section and permitting it to be operated in connection with the body portion upon being positioned in the mouth of the patient.

It is found in some instances, where the jaw and interdentalous spaces and mal-posed and mal-formed teeth, of advantage in order to obtain a correct impression of such teeth, to provide separate and independent molding units for such teeth. These independent molding units 24 being preferably formed cup-shaped as best illustrated in Figures 7 and 8, and are separable along their center line as at 25 and are provided with inturned fracture ridges 26 along their meeting edges, the same being preferably formed of lead or other soft materials, permitting their edges to be cut and shaped to fit the gum of the patient, the closed ends 27 of these cups being so shaped that they are adapted to set into the impression material in the rear of the trough-shaped portion of the body member of the tray. These molding units may be set into the body of the tray and be, themselves, filled with impression material, whereby these independent molding units are adapted to take an impression of such unusual teeth and at the same time that the im-

pression of the rest of the jaw is being taken in the body of the tray. After the whole impression is taken the front removable section is first withdrawn to obtain a correct impression of the front or labial surface of the anterior teeth and to permit a free removal of the body of the tray from the rear portion of the jaw; next the body portion of the tray is removed leaving the independent mold units still connected to the posterior teeth; next these individual molds or units are split apart by the use of a wedging instrument, their fracture ridges serving to split the plaster or impression material on the desired line, to permit of its ready removal. These units are then again reassembled and repositioned in their depressions in the impression material in the main body of the tray; then the front section is again positioned on the body portion and the whole is then ready to receive the molding material which is poured thereinto, whereby an absolutely correct reproduction of the teeth and interdentalous spaces, is obtained, together with that of the mal-posed or mal-formed teeth which were obtained in the individual molds.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A dental impression tray comprising a channeled body portion shaped to carry impression compound and take a full jaw impression, and having an independent front section adapted to be positioned on said body portion to complete the front portion thereof for taking the impression, said section being readily removable to be separated and taken from the body with that portion of the compound carried by it after the impression has been taken.

2. A dental impression tray having a channeled body portion shaped to carry impression compound and take a full jaw impression, an independent front section adapted to be positioned on said body to be readily separated and removed therefrom and having a cleavage ridge on the line of separation, whereby it may be removed with that portion of the compound carried by it after the impression has been taken.

3. A dental impression tray having a channeled body portion shaped to take a full jaw impression, an independent front section removably mounted on said body to be separated and taken therefrom, and having a cleavage ridge on the line of separation, and guiding means to assist in re-positioning said section after having been removed from the body portion.

4. A dental impression tray having a channeled body portion shaped to take a full jaw impression, an independent front section carrying a separate front wall portion, 5 said front wall and a portion of the bottom wall being removably mounted on said body, whereby it may be separated and taken from said body.

5. A dental impression tray having a channeled body portion shaped to take a 10 full-jaw impression, a front section carry-

ing the front wall, and a portion of the bottom wall removably mounted on said body and having a cleavage bottom ridge on the line of separation, an operating handle on 15 said body, and a cooperating handle on said section whereby said section and body may be manipulated either collectively or separately.

In testimony whereof I affix my signature.

WILLIAM N. KIDDER.
